[57] ABSTRACT

The specification discloses a signboard construction comprising a plurality of longitudinally extending, interlocking face pieces adapted to be secured to a supporting frame with means formed on the opposite edges of such interlocking pieces forming longitudinally extending rails adjacent to the opposite edges of such interlocking pieces for supporting a plurality of letters or figures on such signboard.

FIG. 2

FIG. 1

FIG. 4

FIG. 3

SIGNBOARD CONSTRUCTION

BACKGROUND OF THE INVENTION

1. Field of the Invention

The present invention pertains to signboards, billboards or marques formed of a plurality of individual replaceable panels for displaying letters or advertising information which is removably secured to such signboard.

2. Description of the Prior Art

There are various prior art signboards on which letters and other advertising media may be removably affixed by means of clips or other latching devices that connect a plurality of longitudinally extending flanges or ridges formed on the face of a signboard. In many of the prior art devices, the signboard is formed of a single sheet of relatively thin metal, such as aluminum or other sheet metal product, with several rows of parallel ridges or other connecting means being formed in a single sheet. With this arrangement, when the sign is struck by various objects, such as bottles or bricks thrown by vandals or children at play, the face of the signboard is bent and distorted so as to make it difficult or impossible to arrange the letters or advertising media in neat, orderly rows on the signboard. It is frequently necessary to replace the entire signboard in order to repair or recondition a damaged sign.

Also, in many of the prior art signboards no provision is made for preventing water from running down the face of the signboard which tends to cause streaks or stains that discolor and thereby detract from the overall appearance of the signboard.

SUMMARY

The signboard of the present invention includes a plurality of longitudinally extending strips of a width which approximates the height of the letters or other advertising material to be placed thereon and having a pair of rails formed at the opposite edges of each individual strip for interlocking with adjacent strips to form a unitary signboard for supporting letters on such signboard. Another object of the present invention is to provide a new and improved signboard construction formed of a plurality of individual panels corresponding in width to the approximate height of the letters carried thereon, wherein such strips include an L-shaped flange at the opposite edges thereof for receiving clips on the letters and also for providing lateral drainage channels for conducting water which may fall on the face of the signboard laterally to the opposite edges of such signboard to thereby prevent water from running down the face of the signboard and staining or otherwise discoloring the board.

The further object of the present invention is to provide a new and improved signboard construction wherein the face of the signboard comprises a plurality of one to two longitudinally extending individual panels which may be stapled or riveted to a support frame so that individual panels may be removed and replaced in the event they are bent or otherwise damaged. With this arrangement, individual panels may be removed and replaced without disturbing the remaining panels comprising the face of the signboard.

BRIEF DESCRIPTION OF THE DRAWINGS

FIG. 1 is a partial front elevation of the signboard of the present invention showing the individual panels comprising the face of the signboard secured to a support frame;

FIG. 2 is an enlarged transverse sectional view of the signboard construction shown in FIG. 1 showing details of the construction of such signboard; and

FIG. 3 is an enlarged end view of one of the panels of the signboard showing details of construction thereof.

FIG. 4 is a sectional view showing the interlocking relationship of the panels forming the sign face.

DESCRIPTION OF THE PREFERRED EMBODIMENT

Briefly, the signboard construction of the present invention, which is designated generally S in FIG. 1, comprises a plurality of longitudinally extending panels P, parallel upper and lower rails U and L respectively, for receiving the clips which support the letters A on the face of the signboard S. As shown in FIG. 4 of the drawings, the rails L and U interlock to form a substantially continuous face of the signboard and yet permit panels P to be removed and replaced in the event that the sign is damaged and needs repair.

Considering now the signboard construction of the present invention in more detail, the panels P include a substantially vertically extending face member 13 having an upper forwardly extending right angle portion 14 and a lower forwardly extending right angle portion 15 which project substantially parallel to each other and forwardly of the face portion 13. An upwardly extending leg member 16 extends upwardly and is inclined forwardly from the forwardmost end 15-A of the lower flange 15 and similarly, an upwardly extending leg 17 projects forwardly and upwardly from the forwardmost end 14-A of the right angle member 14.

As best seen in FIG. 3 of the drawing, the upper leg 17 includes the U-shaped upper portion 20 with an inner leg or strip 22 that is folded over and downwardly so as to extend along the inner side of the upper leg 17. As shown, the innermost end 22-A of the inner leg 22 is spaced rearwardly from the rear side like, as the forward leg 17 so as to provide a gap indicated by the arrow 25 for receiving the lower leg 16 of next adjacent panel P.

A plurality of such panels P are shown secured to a frame member 30 by means of a plurality of spaced rivets or screws 33 which extend through suitable openings in the face portion 13 of the panel P and are anchored in the support frame member 30. Such support frame member 30 may either be strips of wood or metal or the like, as desired. Of course, it should be appreciated that the panel members P may be attached to opposite sides of such support strips 30 in the event it is desired to provide a sign having display faces on opposite sides thereof.

As shown in FIG. 1 of the drawing, the rivets or screws 33 are preferably attached through the ends of the panels P with the support frame 30 comprising a perimeter frame. However, the screws or rivets 33 may be positioned at other points on the panels P if desired.

The letter "A" shown in FIG. 2 of the drawings is provided with upper and lower clip members or han-

gers 40 which are secured to the letter "A" by means of suitable pins 41 or other suitable connecting means. Such letter "A" may either be formed of masonite, metal, plastic or other suitable material as desired.

As best seen in FIG. 2 of the drawings, when adjacent panels P are secured to the support frame 30, the lower leg 16 is shown extending into the upper U-shaped leg 20 to provide an interlocking construction with each of the face panels P secured to the other panels adjacent thereto.

In constructing the signboard of the present invention, it will be appreciated that a plurality of longitudinally extending panels P, which may either be painted or otherwise prepared for use outdoors, are shaped to conform to the arrangement shown in FIG. 3 and 4 of 15 the drawings with the upper U-shaped leg portion 17 and a lower forwardly and upwardly inclined leg 16 adapted to and extending to the open U-shaped end of the upper legs 17. Such adjacent panels P are connected together by sliding one longitudinally into the 20 other with the lower leg member 16 inserted through the opening 25 in the upper leg 17, with a plurality of such legs secured in interlocking fashion, the opposite ends of such panels may then be fastened or affixed to the supporting frame 30 by means of a plurality of 25 rivets 33, screws or other suitable securing means which may be quickly and easily removed to facilitate the removal and replacement of individual panels P from the signboard S.

It will be appreciated that with the signboard construction on the present invention, in the event water or other liquids fall on such signboard surface that the liquids will be drained laterally to the ends of the individual panels P rather than run down the face of such signboard to discolor or stain it.

The foregoing disclosure and description of the invention are illustrative and explanatory thereof, and various changes in the size, shape, and materials as well

as in the details of the illustrated construction may be made without departing from the spirit of the invention.

What is claimed is:

1. A signboard construction for supporting removable letters and numbers comprising
  - a support frame,
  - a plurality of longitudinally extending interlocking sheet panels adapted to be connected together to form a signboard face,
  - means for securing said individual sheet panels to said support frame,
  - each of said longitudinally extending panels including:
    1. a substantially plane face member disposed substantially parallel to said support frame,
    2. a lower lateral member projecting forwardly from the lower edge of said face member,
    3. An upper leg extending forwardly and upwardly from the forward end of said lower lateral member,
    4. an upper lateral projection extending forwardly from the upper end of said face panel and substantially parallel to said lower lateral projecting member,
    5. an inverted U-shaped channel projecting upwardly and forwardly from the forward end of said upper lateral projection for receiving the upper leg of the lower lateral member when two adjacent panels are interlocked together to provide a continuous signboard face with longitudinally extending channels therein and for receiving and supporting a plurality of letters thereon.
2. The invention of claim 1 wherein said panel members are each substantially the same width as the height of the letters affixed thereto.
